[57] CLAIM

The ornamental design for an electric shaver with a beard-styling attachment, as shown and described.

DESCRIPTION

FIG. 1 is a perspective front view of an electric shaver with a beard-styling attachment from above, showing my design; FIG. 2 is a front view of the appliance of FIG. 1; FIG. 3 is a right-side view of the appliance of FIG. 2; FIG. 4 is a left-side view of the appliance of FIG. 2; FIG. 5 is a rear view of the appliance of FIG. 2; FIG. 6 is a top plan view of the appliance of FIG. 2; and, FIG. 7 is a bottom plan view of the appliance of FIG. 2. The unshaded region within the circular boundary of the bottom surface enclosing the oblong and rectangular regions forms no part of the claimed design.
